TEMPERATURE REGULATOR FOR SECONDARY VOLATILE REFRIGERANT CIRCUIT

Carl F. Alsing, Wilbraham, Mass., assignor to Westinghouse Electric Corporation, East Pittsburgh, Pa., a corporation of Pennsylvania

Application June 17, 1947, Serial No. 755,090

7 Claims. (Cl. 62—4)

1

This invention relates to secondary volatile refrigerant circuits and, more especially, to a temperature regulator for such circuits.

It is an object of the invention to provide a novel regulator for varying the heat-transferring action of a secondary volatile refrigerant circuit.

It is a further object of the invention to provide a novel regulator of the type described which has no moving parts to effect a variation in its heat-transferring action.

These and other objects are effected by the invention as will be apparent from the following description and claims taken in connection with the accompanying drawings, forming a part of this application, in which:

Fig. 1 is a vertical section of a refrigerator cabinet embodying the invention, the cooling elements being shown somewhat schematically;

Fig. 2 is an enlarged sectional view of the regulating receptacle of this invention showing one phase of its operation;

Fig. 3 is a view similar to Fig. 2 but showing another phase of the operation of the receptacle;

Fig. 4 is a section on the line IV—IV of Fig. 3;

Fig. 5 is a section on the line V—V of Fig. 1;

Fig. 6 is a vertical sectional view of a refrigerator embodying a modification of the invention;

Fig. 7 is an enlarged sectional view of the regulating receptacle shown in Fig. 6; and

Fig. 8 is an enlarged sectional view of a modification of the regulating receptacle shown in Fig. 6.

In the drawings, the reference numeral 10 designates the food storage cabinet of a refrigerator, the cabinet having thermally-insulated walls 12 and a door 14. A horizontal partition 16 divides the cabinet 10 into an upper compartment 18 for the storage of frozen food and into a lower compartment 20 for ordinary refrigerated storage. A machine compartment 22 is located below the food storage compartment 10 which compartment 22 houses the refrigerant liquefying apparatus of the refrigerator.

The upper compartment 18 is cooled by a refrigerant evaporator 24 in the form of a tube. The vaporized refrigerant is removed from the evaporator 24 through a suction tube 26 by a compressor (not shown) located in a sealed casing 28. The compressor is driven by an electric motor (not shown) also located in the sealed casing 28. The compressed refrigerant vapor is conveyed from the compressor through a tube 30 to an air-cooled condenser 32. Cooling air ambient the cabinet 10 is drawn through the louver 34 in the machine compartment 22 and through

2

the condenser 32 by an electrically-driven fan 36. The cooling air passes over the sealed casing 28 and leaves the machine compartment 22 through the louver 38. The refrigerant vapor is liquefied in the condenser 32 and is forced through a capillary tube 40 to the lower end of the evaporator 24 wherein it vaporizes and cools the compartment 18 to a temperature of about 0° F. Portions of the capillary tube 40 and the suction tube 26 are in heat-transfer relation.

The electric motor (not shown) in the sealed casing 28 is supplied with electrical energy through leads 42. A thermostatically-controlled switch 44 is located in one of the leads 42 and is actuated through a tube 45 by a temperature-responsive bulb 46 located in the upper compartment 18. Such thermostats are well known in the art.

The lower compartment 20 is cooled by a secondary volatile refrigerant circuit which includes a receptacle 50 located in the thermal insulation of the rear wall of the food storage cabinet 10. The receptacle 50 is divided by a horizontal partition 52 into an upper compartment comprising a refrigerant transfer chamber 54 and a lower compartment comprising a liquid refrigerant storage vessel 56. The partition 52 includes an elevated portion in its center having an orifice 58 in its upper wall. A needle 60 is secured to the center of the upper wall 62 of the receptacle 50 and enters the orifice 58 with its pointed end to restrict the flow of fluid through the orifice 58. The upper wall 62 is rendered flexible by a circular groove 64, and its center together with the needle 60 may be raised or lowered by turning an adjustment screw 66. The screw 66 is in threaded engagement with the central portion of a bail 68, the ends of which are secured to the side walls of the receptacle 50.

A secondary evaporator 70 is located in the lower compartment 20 to cool it to a temperature of about 40° F. The secondary evaporator 70 is in the form of a sinuous tube, the upper end 72 of which communicates with the upper portion of the transfer chamber 54 and the other end 74 of which communicates with the lower portion of the transfer chamber 54.

A blind tube 76 has an upper portion 78 in heat-transfer relation with the primary evaporator 24. This upper portion 78 constitutes the secondary condenser of the secondary system. The lower portion 80 of the blind tube 76 enters the transfer chamber 54 near the upper wall 62 and continues downwardly through the partition 52 to the lower portion of the storage vessel 56.

This tube portion 80 is in fluid-tight engagement with the wall of the transfer chamber 54 and with the partition 52. An opening 82 is located in the tube portion 80 immediately above the partition 52 and a second opening 84 is located in the tube portion 80 above the opening 82 to communicate with the upper portion of the transfer chamber 54. The bottom wall of the storage vessel 56 is in heat-transfer relation with the capillary tube 40. The secondary system is evacuated and a quantity of refrigerant is introduced therein which quantity is such that when the refrigerator is in operation and all of the refrigerant liquid is in the storage vessel 56 the liquid level of the refrigerant liquid will not be 15 above the lower portion of the partition 52. This condition is shown in Fig. 2.

Operation

The secondary volatile refrigerant circuit and its regulating device operates as follows: Refrigerant vapor is condensed by the upper portion 78 of the tube 76 and flows downwardly into the storage vessel 56. If no heat is applied to the storage vessel 56 by the capillary tube 40, the refrigerant liquid will remain in the vessel 56 as is shown in Figure 2. A small amount of this liquid will vaporize and pass through the orifice 58 and the opening 84 to the condensate portion 78 of the tube 76 but on being condensed will again return to the vessel 56. Under these conditions the lower compartment 20 is not refrigerated because no refrigerant liquid is supplied to the secondary evaporator 70.

If heat is applied to the vessel 56 by the capillary tube 40, more of the refrigerant liquid in the vessel 56 will vaporize. The restrictive effect of the orifice 58 is so adjusted by the screw 66 that the additional flow of vapor causes a back pressure to form in the vessel 56 which pressure is higher than that in the secondary evaporator 70. This pressure causes the refrigerant liquid to rise in the lower portion 80 of the tube 76 to a level above the opening 82 as illustrated in Figure 3. The liquid, thereupon, runs through the opening 82 into the transfer chamber 54 and flows downwardly through the tube 74 into the secondary evaporator 70. The opening 82 thus forms a spillway for the liquid. The refrigerant liquid absorbs heat from the lower compartment 20, vaporizes, and passes through the upper end 72 of the evaporator 70 into the transfer chamber 54 and then through the opening 84 to the condensate portion 78 of the tube 76. On being condensed, the liquid runs down through the tube 76, and since its entrance into the vessel 56 is opposed by the higher pressure therein, the liquid flows through the opening 82, over the partition 52, and downwardly through the end 74 and into the evaporator 70. This action continues and cools the secondary evaporator 70.

The degree of cooling effected in the secondary evaporator 70 varies with the quantity of refrigerant liquid transferred to it through the end 74 by the receptacle 50. This quantity varies with the temperature of the capillary tube 49 and this in turn varies with the temperature of the room air which cools the condenser 32 and upon the proportion of the running time of the primary refrigerating apparatus to its idle time. This proportion also varies with the temperature of the room in which the refrigerator is located so that the quantity of cooling effected by the secondary evaporator 70 varies substantially with the room temperature. The higher

the room temperature, the greater will be the cooling effect of the evaporator 70. This greater cooling effect tends to offset the greater heat leakage into the compartment 20 in the higher room temperature so that the variations in the cooling effect of the evaporator 70 tend to maintain the temperature of the lower compartment 20 constant in varying room temperatures. The substantially constant temperature at which the lower compartment 20 is maintained may be changed by adjusting the screw 66 which may be turned by any suitable means.

The regulating apparatus of this invention can also be actuated by exposing the vessel 56 to the room air so that the pressure within the vessel 56 becomes responsive to the temperature of the room air. This, however, transfers heat into the cabinet and is not favored.

Modifications

A modification of the invention is shown in Figs. 6 and 7. In these figures parts identical with those shown in the previous modification are provided with the same reference numerals. Referring to Fig. 6, the reference numeral 100 designates a secondary evaporator similar in function to the evaporator 70 of Fig. 1. The upper end of the evaporator 100 is joined by a tube 102 to the upper end of the tube 104 which constitutes the secondary condenser so that the refrigerant vaporized in the secondary evaporator 100 passes directly to the secondary condenser 104. The refrigerant condensed in the secondary condenser 104 flows through a tube 106 to the lower portion of a vessel 108 which vessel has a function similar to the vessel 56 of the previously-described modification. A vertical tube 110 communicates through an upwardly-arched portion 112 with a portion of the tube 106 located in the upper part of the vessel 108. This tube 110 communicates with the lower end of the evaporator 100. The upper portion of the vessel 108 also communicates through a tube 113 and a needle valve 114 with the upper portion of the secondary evaporator 100. The quantity of refrigerant in the secondary system is such that the refrigerant liquid in the system, if entirely contained in the vessel 108, will have an upper level 116 which is below the arched portion 112 of the tube 110 so that the liquid does not run into the tube 110. This condition is shown in Fig. 7.

The operation of this modification is similar to the modification previously described. The heat of the capillary tube 40 vaporizes some of the liquid in the vessel 108 and this vapor passes through the tube 113 and the needle valve 114 to the secondary condenser 104 wherein it is liquefied and is returned to the vessel 108 through the tube 106. When the heat of the capillary tube 40 exceeds a predetermined degree, the refrigerant vapor passing through the needle valve 114 will encounter sufficient resistance to create a back pressure in the vessel 108, which back pressure elevates the refrigerant liquid level in the tube 106 to above the arched portion 112 of the tube 110 so that the refrigerant liquid will run into the evaporator 100. The lower inner surface of the arched portion 112 thus forms a spillway for the liquid.

The refrigerant liquid vaporized in the evaporator 100 will pass upwardly directly to the secondary condenser 102, will be liquefied therein, and will flow through tubes 106 and 110 to the evaporator 100. The quantity of refrigerant liq-

uid expelled from the vessel 108 will depend upon the quantity of heat transmitted to the vessel 108 by the capillary tube 40 at any given setting of the needle valve 114. The needle valve 114 may be adjusted to vary the quantity of refrigerant liquid supplied to the evaporator 100 for any given temperature of the capillary tube 40.

A modification of the piping in the vessel 108 is shown in Fig. 8. In this modification, the tube 120 which corresponds to the tube 110 of the previous modification communicates directly with a lower portion of the vessel 108 through an elevated portion 122. This figure shows the vessel 108 under pressure so that the liquid level in the tube 108 is elevated and the refrigerant liquid runs over the elevated portion 122 of the tube 120. The action of this modification differs from that of the modification shown in Fig. 7 in that a siphoning action may take place across the elevated portion 122 whenever the refrigerant liquid starts to flow through the same. This siphoning action will draw out some of the refrigerant liquid from the vessel 108 so that the liquid supplied to the evaporator 100 will be of a pulsating character.

The general action of the three modifications shown is that the refrigerant liquid condensed by the secondary condenser flows into the liquid storage vessel and will be substantially completely trapped therein if the storage vessel is not heated. If the vessel is heated in response to increases in the room temperature, some of the refrigerant liquid will be forced from the vessel over an elevated spillway and will then run into the secondary evaporator. Also, when the vessel is heated, liquid refrigerant from the condenser will either by-pass the vessel completely and flow into the secondary evaporator or will merely flow through the vessel on its way to the secondary evaporator.

It will be apparent from the above that this invention provides an automatic regulating device for a secondary volatile refrigerant circuit which has no operating moving parts and which tends to maintain the chamber cooled but at a substantially constant temperature in spite of varying ambient temperatures of the refrigerated cabinet. The invention also provides a manual adjustment for changing the substantially constant temperature at which the chamber is maintained.

While I have shown my invention in several forms, it will be obvious to those skilled in the art that it is not so limited, but is susceptible of various other changes and modifications without departing from the spirit thereof.

What I claim is:

1. In a refrigerating system, the combination of a cabinet having a space to be refrigerated, a refrigerant evaporator for abstracting heat from media in said space, a refrigerant condenser disposed exteriorly of the space, a vessel for containing a body of liquid refrigerant, means for applying heat to said vessel in proportion to the temperature of the atmosphere ambient said cabinet for varying the temperature and pressure of said body of refrigerant directly in response to changes in temperature of the ambient atmosphere, a conduit structure connected to the condenser and terminating in a lower region of the vessel for draining condensed refrigerant by gravity from the condenser to the vessel, means defining an overflow passage for the body of liquid refrigerant in the vessel, means for draining refrigerant, overflowing through said passage, by

gravity to the evaporator, means for conveying vaporized refrigerant from the evaporator to the condenser and adjustable valve means connecting an upper region of said vessel and said vaporized refrigerant conveying means for the passage of vaporized refrigerant.

2. In a refrigerating system, the combination of a cabinet having a space to be refrigerated, a refrigerant evaporator for abstracting heat from media in said space, a refrigerant condenser disposed exteriorly of the space, a vessel for containing a body of liquid refrigerant, means for applying heat to said vessel in proportion to the temperature of the atmosphere ambient said cabinet for varying the temperature and pressure of said body of refrigerant directly in response to changes in temperature of the ambient atmosphere, a conduit structure connected to the condenser and terminating in a lower region of the vessel for draining condensed refrigerant by gravity from the condenser to the vessel, said conduit structure having an overflow opening in an intermediate portion thereof for condensed refrigerant, means for draining refrigerant, overflowing through the opening, by gravity to the evaporator, means for conveying vaporized refrigerant from the evaporator to the condenser and means for defining an orifice for the passage of refrigerant vapor from the vessel to said vaporized refrigerant conveying means.

3. In a refrigerating system, the combination of a cabinet structure having an enclosed space for media to be cooled, a condenser, an evaporator for cooling the media in said space, a compartmented vessel having first and second chambers, a conduit structure for conveying liquid refrigerant from the condenser to said second chamber, said conduit structure having an intermediate portion in open communication with said first chamber for the passage of gaseous refrigerant from the first chamber to the conduit structure, said intermediate portion of the conduit structure providing for the overflowing of liquid refrigerant from the conduit structure to the first chamber, means for conveying liquid refrigerant from the lower region of the first chamber to the evaporator, means for discharging gaseous refrigerant from the evaporator to the first chamber, means for applying heat to said vessel in proportion to the temperature of the ambient atmosphere exteriorly of the cabinet structure for varying the pressure of the refrigerant in said second chamber directly with changes in temperature of said ambient atmosphere and means defining a restricted orifice providing communication between said first and second chamber.

4. The combination as claimed in claim 3 wherein said first chamber is elevated with respect to the second chamber.

5. The combination as claimed in claim 3 including adjustable means disposed, at least in part, exteriorly of the vessel for adjusting the flow area of said orifice.

6. In a refrigerating system, the combination of a cabinet defining a space to be refrigerated, a condenser, an evaporator for cooling media in said space, a vessel having a partition dividing the vessel into upper and lower chambers, said partition having an orifice for the flow of refrigerant vapor from the lower chamber to the upper chamber, a conduit structure communicating with said condenser and extending downwardly therefrom through said upper chamber and terminating adjacent the bottom region of the lower chamber for the delivery of condensed refriger-

erant therein, said conduit structure having an overflow opening therein for the delivery of condensed refrigerant to the lower region of the upper chamber, said conduit structure having a second opening therein communicating with an upper region of the upper chamber for the passage of refrigerant vapor to the conduit structure, means for conveying condensed refrigerant from the lower region of the upper chamber to the evaporator, means for conveying vaporized refrigerant from the evaporator to the upper chamber, and means for applying heat to said vessel in proportion to the temperature of the ambient atmosphere exteriorly of said cabinet for varying the pressure of the refrigerant in 15 said lower chamber directly in response to

changes in temperature of the ambient atmosphere.

7. The combination as claimed in claim 6 including adjustable means disposed, at least in part, exteriorly of the vessel for varying the flow area of said orifice.
